UNITED STATES PATENT OFFICE.

OTIS ORA FUSCH, OF BELLFLOWER, CALIFORNIA.

DOUBLE-PISTON TWO-CYCLE ENGINE.

Application filed October 29, 1924. Serial No. 746,565.

I have entitled my invention as a double piston two cycle engine, as this is my present preferred use of the features of my invention.

5 The invention in its broad features comprises a stationary cylinder, a piston reciprocating therein, a stationary piston inserted within the cylinder and over which the reciprocating piston reciprocates. This 10 basic mechanism, with suitable valves, inlets and outlets, may be used as an internal combustion engine of the two cycle and the four cycle type. It may be used as a single or double expansion steam engine. By applying power to operate the moving piston the 15 structure may be used as a gas compressor of the single or two stage type.

My invention of the two cycle engine type is designed to overcome some of the disadvantages of the present type in which the 20 fuel gas is compressed in the crank chamber before entering the explosion cylinder. I also am enabled to provide a forced feed of lubrication for the pistons and connecting rods instead of having to mix lubricating oil with the power fuel such as gasoline.

The broad features of my two cycle internal combustion engine comprise a stationary outer cylinder, a piston reciprocating 30 therein, a stationary piston mounted inside of the cylinder and over which the reciprocating piston slides. A connecting rod is secured by a wrist pin to the reciprocating piston and operates a crank shaft in the usual manner. In the specific operation 35 of this engine, on the upstroke of the reciprocating piston, gas is sucked into the inner chamber between the stationary and the reciprocating piston. On the downward movement of the reciprocating piston 40 the gas is forced out of this inner chamber and into the outer chamber between the cylinder and the reciprocating piston. On the second upstroke the gas in the outer 45 chamber is compressed and fresh gas is drawn into the inner chamber. At the top position the explosion is caused by the usual spark plug giving the explosion stroke to the reciprocating piston. Near the end of 50 the downstroke the exploded fuel is lead out of the ordinary two cycle exhaust port.

Thus on the explosion stroke the gas is compressed in the inner chamber and forced into the outer chamber. On the compres-

sion stroke in the outer chamber fresh gas 55 is drawn into the inner chamber. I thereby obtain a two cycle engine in which the fresh fuel is drawn and compressed within the body of the reciprocating piston.

An important function of this operation 60 is the cooling of the reciprocating piston by the fresh fuel gas being drawn into the inner chamber inside of the reciprocating piston. I may provide, if necessary, means for circulating water passages in the stationary 65 cylinder.

My invention will be more clearly understood from the following specification and accompanying drawings, in which

Figure 1 is a transverse section through 70 the engine with the reciprocating piston in its upper position.

Fig. 2 is a section of Fig. 1 on the line 2-2 looking up as indicated by the arrows, 75 showing the base of the stationary cylinder.

Fig. 3 is a section of Fig. 2 on the line 3-3 in the direction of the arrows showing the wrist pin details.

Fig. 4 is a diagrammatic view of the engine with the reciprocating piston in its 80 lowermost position.

Referring to Fig. 1, a cylinder A is mounted on a crank case B. A reciprocating piston C operates on the inside of the cylinder A and on the outside of the stationary piston D, which latter is rigidly attached to the crank case or cylinder at its lower end. 85

The cylinder A is of the usual two cycle type with an outer wall 1, flange 2, water jacket 3, spark plug 4, inlet port 5 and the 90 outlet port 6. The duct 7 to convey the fuel to the intake port is different from the usual construction.

The reciprocating piston C so far as the upper portion 10 is concerned is similar to 95 the present two cycle pistons, having a baffle 11 on the piston head 12 to deflect the incoming gas. I preferably extend the cylinder walls on each side forming skirts 13 in which the wrist pin is secured, the detailed 100 fastening of which is shown in Fig. 2. The bushings 14 are fastened on the inside of the skirts by means of screws 15. The wrist pin 16 is mounted in these bushings. The usual piston rings 17 maintain the compression in what I term the outer chamber between the cylinder and the piston head 12.

The stationary piston, I believe, is of an

entirely new construction, having a cylindrical wall 20, a piston head 21, and flange 22 with piston rings 23 to maintain the compression in what I term the inner chamber between the inside of the reciprocating piston and the piston head 21. The stationary piston has a duct 24 leading through the flange 22, shown on the right hand side, forming an intake passage from the carburetor manifold 25. This leads upward through a duct 26 to an intake valve 27 in the piston head 21. If desired, an enlarged intake chamber 28 can be formed as an extension of the intake 26. The valve 27 is shown with a spring 28^a engaging a spider 29 across the valve opening and the valve stem 30, so as to maintain the valve head 31 seated but allow it to open when gas is sucked into the inner chamber.

20 The outlet from the inner chamber is through the compression valve chamber 35 in which a valve head 36 is held seated by a spring 37 engaging a spider 38 and attached to the valve stem 39. This spring is 25 preferably much stronger than the spring on the intake valve. Below the valve an enlarged compression chamber 40 is formed on the body of the piston and leads into a compression duct 41 which passes through the 30 flange 22 on the left hand side as indicated by 42, and thence connects to the duct 7 of the cylinder as indicated at 43.

The stationary piston is preferably cored to form a water jacket 44 which connects 35 by any suitable conduits such as 45 and 46 with the usual water circulating system of the engine.

40 The stationary piston is preferably recessed from the bottom upward to allow the wrist pin to extend upwardly into the cylinder. However, the construction could be modified in which the wrist pin at its uppermost position would be substantially level with the flanges. In this case, the bearing 45 surface of the inner and outer piston would be lengthened.

In the assembly shown in Fig. 1, the flange 2 of the cylinder and the flange 22 of the stationary piston are bolted to the top 55 of the crank case B by bolts 56. The crank case is preferably formed in two parts, an upper section 57 and a lower section 58, being bolted at the flanges 59. A hand plate 60 may be placed at the bottom if desired. 55 The crank case has the usual brackets 61 for the crank shaft 62 which has the usual crank bearings 63 for the connecting rod 64 of the usual type engaging the wrist pin 16 at its upper end 65.

60 The operation of my engine is as follows: Presuming the reciprocating piston C to be in the lower position, as shown in Fig. 4, on the upstroke gas is drawn in from the carburetor through the ducts 24 and 26 and intake valve 27. The spring 28^a is sufficient-

ly light to allow the valve head 31 to lift with the suction. On the downstroke of the reciprocating piston the gas in the inner chamber between the piston C and the piston head 21 of the stationary piston is compressed and forced out through the compression valve chamber 35. As above mentioned, it is preferable to use a strong spring in this valve so that the gas will be considerably compressed before the valve head 36 lifts 75 from its seat. The compressed gas is forced through the chamber 40 and ducts 41 and 7 to the port 5. The reciprocating piston is now in its lower position so that the compressed gas is forced over the head 12 striking first the baffle 11. The upstroke of the reciprocating piston compresses this gas in the outer chamber and at the same time sucks gas into the inner chamber. The engine is now with the piston in the upper position, 85 as indicated in Fig. 1, ready for the first explosion. This drives the piston down, forces the fuel gas out of the inner chamber and exhausts the exploded gas through the exhaust port 6. As above mentioned, the 90 intake port 5, exhaust port 6 and the baffle 11 are arranged in the ordinary way so that the exploded gas is exhausted while the fresh fuel gas is forced in in the usual two cycle practice. The engine now continues 95 automatically on the two cycle principle and may be controlled by both the usual throttle and spark advance and retardation.

As above mentioned, the gas in the inner chamber cools the reciprocating piston and thereby becomes pre-heated so that hot gas is introduced into the outer or explosion chamber.

My invention in the form of a two cycle engine is open to considerable modification. For instance, the wrist pin as above mentioned could be on substantially the same level as the flanges, in which case it would be desirable to continue a skirt downwardly from the cylinder to form a longer bearing 110 for the reciprocating piston. The water conduits and gas ducts could be suitably positioned to transfer the heat from the water to the incoming gas.

An adaptation of my design to a four cycle engine would be somewhat as follows:

Poppet valves would be mounted in the stationary piston and operated from cam shafts, preferably in the crank chamber. A spark plug would also be situated in the face 120 of the stationary piston.

The cylinder and the reciprocating piston could function as the ordinary four cycle engine, preferably of the overhead valve type, in the usual manner. It will thus be 125 seen that the reciprocating piston would be acted upon by the explosion in the outer chamber and also by the alternating explosion in the inner chamber. This would double the number of impulses to which the re- 130

ciprocating piston and crank would be subject over the ordinary construction, thereby increasing the efficiency of the engine.

The same basic design of a cylinder, a piston reciprocating therein, and a stationary piston over which the reciprocating piston reciprocates could be used as a steam engine of the double expansion type. Through any suitable and well known valve mechanism 5 live steam would be lead through the stationary cylinder into the inner chamber. The exhaust from this inner chamber would be lead through suitable ports to an intake into the outer chamber. By suitably 10 portioning the area of the pistons and the volume of the stroke, the steam could be expanded in succession, the proper amount in each of the chambers. It might be necessary to form an inner false wall on the reciprocating piston in order to decrease the area 15 of the stationary piston and hence the volume of the inner chamber compared with the outer chamber. It will thus be seen that in such a double expansion steam engine the 20 reciprocating piston and crank shaft would act under the impulse of double expansion steam. As well known in the steam engine art, the valves could be operated to cause both the inner and the outer chambers to 25 act as high pressure expansion chambers.

The same basic construction of the reciprocating piston and stationary piston may be adapted to an air and gas compressor of the single or two stage type. In this case 30 the crank shaft would be rotated by some prime mover and the outer chamber would form the first stage of the compression. By suitable valves and ports the air or other gas would be drawn into the outer chamber 35 and exhausted therefrom into the inner chamber and exhausted therefrom as a highly compressed gas.

These merely indicate some modifications 40 of the construction and use of my basic invention. It may be desirable to mount the inner piston in a flexible manner instead of rigidly as shown. This could be done by passing the suction and compressed gases 45 through swiveled sleeves. Such construction would allow slight lateral movement of the 50 stationary piston in reference to the reciprocating piston. It might also be desirable to operate the valves in the head of the inner piston by cams in the same manner as 55 poppet valves in four cycle engines.

Various changes may be made without departing from the spirit of the invention as claimed.

I claim:

60 1. An engine having a crank case, a cylinder supported thereon, a stationary piston having a closed head and side walls partially open from their lower edge, the stationary piston being supported on the lower edge of 65 the side walls inside the cylinder, a sliding

piston having bearing surfaces on the cylinder and the stationary piston, oppositely positioned skirts depending from the sliding piston into the openings in the side walls of the stationary piston, a wrist pin between 70 the skirts, a crank in the crank case, a connecting rod between the crank and the wrist pin, inlet and outlet valves in the head of the stationary cylinder, ducts leading through the side wall portions of the stationary cylinder to said valves and inlet and outlet ports in the cylinder positioned to feed and to discharge gas between the moving piston and the cylinder.

2. An engine having a crank case, a cylinder supported thereon, a stationary piston having a closed head and side walls partially open from their lower edge, the stationary piston being supported on the lower edge of the side walls inside the cylinder, 80 a sliding piston having bearing surfaces on the cylinder and the stationary piston, oppositely positioned skirts depending from the sliding piston into the openings in the side walls of the stationary piston, a wrist pin between the skirts, a crank in the crank case, 85 a connecting rod between the crank and the wrist pin, and a water jacket in the side wall portions of the stationary piston.

3. An engine having a crank case, a cylinder supported thereon, a stationary piston having a closed head and side walls partially open from their lower edge, the stationary piston being supported on the lower edge of the side walls inside the cylinder, a sliding piston having bearing surfaces on the cylinder and the stationary piston, oppositely positioned skirts depending from the sliding piston into the openings in the side walls of the stationary piston, a wrist pin between 90 the skirts, a crank in the crank case, a connecting rod between the crank and the wrist pin, 95 ducts leading through the side wall portions of the stationary piston, valves in the head of the stationary piston connected to said ducts, a water jacket in the side wall portions of the stationary piston and inlet and exhaust ports in the cylinder for the moving piston.

4. An engine comprising in combination 100 a cylinder having valveless inlet and outlet ports, a reciprocating piston having a closed piston head forming therewith an outer chamber, a stationary piston having a head with inlet and outlet valves over which the reciprocating piston reciprocates and forming therewith an inner chamber, a connecting rod attached to the reciprocating piston, 105 a crank shaft connected to the connecting rod, a duct to convey gaseous fuel to the inner chamber through the inlet valve, a duct from the outlet valve to the inlet port of the cylinder and means to explode the gas in the outer chamber.

5. An engine as claimed in claim 4, in 110

which the ducts to the inlet and outlet valves are formed in the body structure of the stationary piston and an additional duct is formed in the cylinder leading to the inlet port of said cylinder.

6. An engine having a cylinder, a piston reciprocating therein, a stationary piston having a head with valves therein, over which the reciprocating piston reciprocates, 10 a water jacket in the stationary piston and means to circulate water therethrough.

7. An engine comprising in combination a crank case, a cylinder extending upwardly from the crank case, a stationary piston having side walls fixedly attached to the crank case, inside the cylinder, a reciprocating piston having a bearing surface in the cylinder and on the outside periphery of the stationary cylinder, said reciprocating piston forming with the cylinder an outer chamber and 15

with the stationary piston an inner chamber, means to conduct a gas through the side walls of the stationary cylinder to and from the inner chamber, means to conduct gas from the inner chamber through the structure of the cylinder to the outer chamber, inlet and exhaust ports in the cylinder for the outer chamber, in which the opposite portions of the side walls are left open and the reciprocating piston has oppositely positioned depending skirts, a wrist pin connecting said skirts and a connecting rod connected to said wrist pin, the inner piston having spring controlled inlet and outlet valves in the head of the said piston, and ducts leading to and from said valves. 25 30 35

In testimony whereof I have signed my name to this specification.
